His Attorney.

UNITED STATES PATENT OFFICE.

CHESTER I. HALL, OF FORT WAYNE, INDIANA, ASSIGNOR TO GENERAL ELECTRIC COMPANY, A CORPORATION OF NEW YORK.

INDUCTION MOTOR.

Application filed June 20, 1924. Serial No. 721,322.

My invention relates to improvements in electric motors of the induction disc type.

One object of my invention is to provide an induction disc motor of improved mechanical construction. Another object is to increase the torque and speed of this type of motor, and another object is to decrease the magnetic hum incident to this type of motor.

Although the novel features of my invention are generally applicable to induction disc motors, the motor is particularly applicable for driving phonographs and the invention will be explained as for such use.

In carrying my invention into effect, I make the magnetic circuit of the motor from a light skeleton casting which constitutes the framework for the motor. The shifting magnetic flux is produced by a plurality of shading coils per pole so arranged as to obtain an unusually large distortion of the flux which cuts the disc. This distortion is further increased and the useless flux which ordinarily cuts the disc is decreased to a minimum by means of a novel magnetic shunt which diverts a portion of the flux away from the disc after it has passed through the shading coils. The result is that the flux that cuts the disc is very efficiently used in producing torque and has an unusually small component perpendicular to the disc which decrease the tendency of the disc to hum due to the magnetic pulsations therethrough.

The features of my invention which are believed to be novel and patentable will be pointed out in the claims appended hereto. For a better understanding of my invention reference is made in the following description to the accompanying drawings in which Fig. 1 shows a plan view of the lower portion of the motor, the upper section of the magnetic framework being removed and a portion of the disc being cut away to better expose the parts; Fig. 2 represents a cross section of the motor taken on line 2-2 of Fig. 1; and Fig. 3 illustrates by way of comparison the difference between a shaded pole having a single shaded coil and one having a plurality of shading coils arranged according to my invention.

Referring now to Figs. 1 and 2, in the present embodiment I have represented the motor as being designed to drive an ordinary disc type phonograph. The framework

and magnetic circuit of the motor comprise two annular castings 10 and 11 arranged to fit together like the base and cover of a cylindrical box. The base portion has three integral pole pieces 12 rising from the skeleton floor and symmetrically arranged at the same distance from the center thereof. In the center of the floor is a step bearing 13 which supports the vertical shaft 14. The shaft 14 carries a worm wheel 15 for driving an adjustable speed governor 16 which is suitably supported in bearing lugs 17 and 18 integral with the casting 10. The shaft 14 also carries the induction disc armature 19 and passes through a guide bearing 20 in the center of the upper casting 11.

The contacting surfaces of the castings 10 and 11 are machined and flanged as illustrated at 21 so as to fit together accurately and the two sections are held together by three screws, one of which is shown at 22. Lugs 23 are provided on the inner wall of the casting 10 to receive these screws. The upper casting has three integral pole pieces 24 depending from its lower side in alignment with the pole pieces 12 rising from the base and the disc 19, which is preferably made of copper, is arranged to rotate in the narrow air gaps thus formed.

The pole pieces 12 are preferably made hollow as illustrated so as to decrease the weight of the motor. The three pole pieces 12 are provided with energizing coils 25 and these three coils may either be connected in series or in parallel across the line. Preferably the three coils will be connected so as to simultaneously produce fluxes in the same direction. This connection and symmetrical arrangement of the pole pieces is in accordance with the invention described and claimed in my copending application Serial No. 639,895, filed May 18, 1923, entitled "Electric drive for phonographs". This arrangement is such that the forces which are perpendicular to the disc and which are produced by the currents set up in the disc reacting against the magnetic fields therethrough are equally balanced with respect to the center line of the shaft 14. Consequently, there can be no resultant force which tends to tip the disc first in one direction and then in another direction. As more fully explained in my prior application, this arrangement substantially elimi-

nates noise and vibration if the disc is made sufficiently thick to resist bending by the forces in question.

By my present invention I have materially reduced the forces which are perpendicular to the disc and at the same time increased the driving torque. Consequently, it is not so essential that the disc be made thick and stiff to eliminate the magnetic 10 hum and the vibration and noise incident thereto.

Instead of using a single shading coil on the pole pieces, as is the usual practice, I provide a number of individual shading coils 15 26, preferably three, as represented. The shading coils are preferably made of copper and are contained in slots 27 milled in the solid tops of the pole pieces 12. The slots in which the shading coils are contained divide the pole face into four sections, A, B, C, and D, section A being unshaded, section B being shaded by one coil, section C shaded by two coils, and section D by all three coils. Since each shading coil displaces the flux 20 which it encircles, it will be seen that the flux in section B lags behind the unshaded flux in section A; that in section C lags behind that in section B and that in section D lags behind that in section C, thus producing a progressive phase displacement of flux.

The three displaced shading coils in the pole faces increase the power output of the motor, and therefore its efficiency, for two 25 reasons; first, the torque is increased over the single shading coil construction because of the fact that the individual poles corresponding to A, B, C, and D are brought closer together giving a shorter effective distance between poles for torque reactions; and second, the speed is increased because the total pole displacement is increased; therefore the shifting field actually travels a greater distance during each cycle. This 40 45 reasoning may be made clear by referring to the diagram in Fig. 3. In this figure 12' and 12 represent two poles, the first having a single shaded section B' and the second three shaded sections B, C, and D. It will be clearly seen that the pole displacements PP₁ in the single shaded pole is much less than in the multiple shaded pole. From this point of view, it will be seen that during one 50 55 cycle the flux shifts a greater distance in the multiple shaded pole and therefore causes a higher speed of rotation of the disc.

Considering the diagram from the point of view of standstill torque, it is seen that the poles must react on poles in the disc 60 through a distance proportional PP₁ in 12'. If the shaded part P₁ be split up into smaller units placed close together as B, C, and D in pole 12 while the pole area and total shaded coil sections are maintained constant, the 65 torque will be increased since the total flux

will remain constant while the individual poles will be closer together. Due to the fact that the attraction varies inversely as the square of the distance, the increased spacing between P and P₁ in pole 12 is more 70 than compensated for by the much shorter spacing between the intermediate poles corresponding to A, B, C, and D.

The provision of a plurality of displaced individual shading coils as above described 75 constitutes an important improvement in this type of motor. I have further improved the motor by the provision of a magnetic shunt 28. It will be seen from an inspection of Figs. 1 and 2 that the solid portions of 80 the pole pieces extend slightly above the shading coils so as to cooperate with a small magnetic shunt 28 secured between the trailing pole tip and the side wall of the casting 10. This shunt is made of soft iron and is 85 preferably keyed into the part D of the pole piece and secured to the frame 10 by means of a screw 29 threaded into a lug 30 in the wall 10. This shunt thus connects the part D of the pole piece above the shading coils 90 with the lower casting forming a parallel path for a portion of the main coil flux which does not cut the copper disc 19. All of the flux which traverses this shunt circuit 95 is effective in creating currents in all three shading coils which in turn causes a greater phase displacement of the flux cutting the disc.

Without the shunt, the currents in the shading coils must be induced by flux which cuts the disc and while the resultant shading coil effect will be greater than with a single shading coil, it will be less than with the shunt for two reasons; first, the shunt increases the total useful flux because it decreases the resultant reluctance of the flux circuit which is now partially across the air gap cutting the disc and partially through the shunt treading all the shading coils; and second, while the flux cutting the disc is not greatly reduced, it is progressively lagged to a greater extent than before because of the increased current in all the shading coils. The resultant direction of the force acting 100 upon the disc due to the reaction between the flux cutting the disc and the currents set up by this flux is now more nearly parallel to the disc and increases the rotative torque and efficiency of the motor and decreases the 105 component of force perpendicular to the disc which is not effective in producing torque 110 and which is detrimental from the point of view of disc vibrations. It may be stated that the resultant effect of this arrangement 115 is to shunt a large proportion of the detrimental component of the flux from the disc which is not effective in producing torque at the same time increasing the torque creative effectiveness of the flux not shunted. Since 120 the flux which cuts the disc is more effective 125 130 135 140 145 150 155 160 165 170 175 180

in creating torque than with the usual shading coil arrangement, the amount of flux necessary to cut the disc may be decreased proportionally which, in turn, has the beneficial result in decreasing the tendency of the disc to vibrate and hum. To obtain the best results, the character of the shunt 28 should be properly proportioned to the remainder of the design in any particular case. For example, if the air gap through which the disc rotates is increased, the reluctance of the shunt should be increased, for instance, by decreasing its cross section or its permeability.

In accordance with the provisions of the patent statutes, I have described the principle of operation of my invention, together with the apparatus which I now consider to represent the best embodiment thereof; but I desire to have it understood that the apparatus shown and described is only illustrative and that the invention may be carried out by other means.

What I claim as new and desire to secure by Letters Patent of the United States, is:

1. An induction motor having a rotatably mounted armature of conducting material, a magnetic member having an air gap through which said armature is arranged to rotate, an energizing winding for said magnetic member, and a plurality of individual shading coils on said member adjacent said air gap for producing a progressive shifting of the flux in the air gap.

2. An induction motor having a rotatably mounted armature of conducting material, a magnetic member having cooperating pole faces on opposite sides of said armature for producing an alternating flux therethrough, an energizing winding for said magnetic member, and a plurality of individual shading coils arranged one within the other on one of said pole faces for producing a progressive shifting of the flux through said armature.

3. An induction motor having a rotatably mounted disc armature, a magnetic member provided with an air gap through which said armature is arranged to rotate, an energizing winding on said magnetic member for producing an alternating flux through said air gap transversely of said disc armature, a shading coil on said magnetic member adjacent the air gap, and means for diverting a portion of the flux threading only said shading coil away from the air gap.

4. An induction motor having a rotatably

mounted armature of conducting material, a magnetic member provided with an air gap through which said armature is arranged to rotate, an energizing winding for said magnetic member for producing an alternating flux through the air gap, a plurality of shading coils on said magnetic member adjacent the air gap for producing a progressive shifting of the flux in the air gap and a magnet shunt for diverting a portion of the flux threading all of said shading coils away from the air gap.

5. An induction motor having a rotatably mounted armature of conducting material, a magnetic member having cooperating pole faces on opposite sides of said armature for producing an alternating flux therethrough, an energizing winding for said magnetic member, a plurality of shading coils on one of said pole faces arranged one within the other and enclosing different areas of said pole faces for producing a progressive shifting of the flux through said armature and a magnetic shunt for diverting flux from the area of said pole face enclosed by all of said shading coils so that it does not pass through said armature.

6. An induction motor provided with a short circuited armature and a single phase field member having an energizing pole adjacent said armature for producing an alternating field therethrough, the pole face thereof being progressively shaded from one side to the other in the direction of rotation and means for shunting flux from the most heavily shaded portion of said pole face away from said armature.

7. An electric motor of the induction disc type comprising a magnetic circuit formed by a pair of skeleton castings fitted together like the base and cover of a cylindrical box, the castings having symmetrically arranged internal pole pieces integral with said castings and extending towards each other from the base and cover positions of the structure, the upper and lower pole pieces being separated and aligned to form air gaps, an energizing coil for each pair of aligned pole pieces, means for shifting the fluxes of said pole pieces within the air gaps, a vertical shaft rotatably mounted in the center of said structure, and a disc of conducting material on said shaft extending into said air gap.

In witness whereof, I have hereunto set my hand this 17th day of June, 1924.

CHESTER I. HALL.
